(57) **CLAIM**

The ornamental design for card reader, as shown and described.

DESCRIPTION

FIG. 1 is a front perspective view of a card reader showing my new design;

FIG. 2 is a top plan view of the card reader;

FIG. 3 is a bottom plan view of the card reader;

FIG. 4 is a front elevational view of the card reader;

FIG. 5 is a rear elevational view of the card reader;

FIG. 6 is a right side elevational view of the card reader; and, FIG. 7 is a left side elevational view of the card reader.

The broken lines in the drawings illustrate unclaimed portions of the card reader and form no part of the claimed design.
